UNITED STATES PATENT OFFICE.

EDWARD N. ANKETELL, OF NEW HAVEN, CONNECTICUT, ASSIGNOR TO THE A. C. GILBERT COMPANY, OF NEW HAVEN, CONNECTICUT, A CORPORATION OF CONNECTICUT.

SEWING-MACHINE MOTOR.

Application filed June 10, 1919. Serial No. 303,142.

To all whom it may concern:

Be it known that I, EDWARD N. ANKETELL, a citizen of the United States, residing in New Haven, county of New Haven, and 5 State of Connecticut, have invented certain new and useful Improvements in Sewing-Machine Motors, of which the following is a full, clear, and exact description.

This invention relates to electric motors 10 for driving sewing machines and the like, and it pertains more especially to a motor driving attachment applicable to various makes of sewing machines. The invention has particular reference to that class of 15 devices wherein the electric motor drives the hand wheel of the sewing machine by means of a drive pulley on the motor shaft frictionally engaging said wheel; and in some phases of the invention, the latter is 20 particularly concerned with a sewing machine driving attachment involving a motor member or unit, which can be readily detached from the sewing machine, when desired, and used for various other purposes, 25 such as mixing beverages, operating a massage vibrator, etc.

One of the primary objects of the invention is to furnish an attachment which 30 can be applied to existing sewing machines of many different makes in a ready and convenient manner.

Another object is to provide a simple and efficient motor attachment of the portable type, which can be used equally well 35 with machines of different patterns having the usual differences in the diameter of the hand wheel, the length and height of the head, and other differences.

I also have in view the provision of a 40 simplified and improved type of motor driven sewing machine wherein the motor member can be readily moved out of its cooperative relation with the hand wheel when said motor member is not in use into 45 a location wherein it is conveniently stored away or accommodated until further use is required of it. This feature is of special advantage in the case of a drop-head machine, because when the motor member is 50 moved out of the operative position into the inoperative position, it is located or accommodated substantially within the lines of the sewing machine head, so that the latter can be dropped into or housed in

the sewing machine table in the usual manner. In the particular embodiment selected for illustration, the power driving mechanism is also detachable from the machine head, as above intimated, but while this is important in certain aspects of the invention, it is unimportant in other aspects. 55

To these and other ends the invention consists in the novel features and combinations of parts to be hereinafter described and claimed. 60

In the accompanying drawings:

Fig. 1 is a fragmentary rear elevation of a sewing machine structure embodying my improvements. In this view, the stored away position of the motor member is indicated in dotted lines. 70

Fig. 2 is a top plan view of the parts shown in Fig. 1.

Fig. 3 is a fragmentary end elevation of the machine head. 75

Fig. 4 is an elevation of the attaching frame or bracket, the machine head and the motor member being shown in dotted lines.

Fig. 5 is a section on 5—5 of Fig. 4; and 80

Fig. 6 is a detail of the bracket or frame detached from the other parts. 85

In the drawings, I have shown one embodiment of my invention applied to a sewing machine of well-known type having a head 20 only partially shown, and the usual machine wheel or hand wheel 21 fixed to the customary shaft 22, which has a bearing in the end of the head as usual. At the wheel end of the head, the latter has the ordinary standard or pedestal 20^a, which extends upwardly from the customary metal bed plate 23. At the top of the standard or pedestal is the usual lateral extension or arm 20^b, which carries the presser bar and needle bar (not shown). In the particular form shown, a motor driving attachment including an electric motor member 24 is detachably secured to the machine head by means of a removable frame member or bracket 25 located alongside the pedestal 20^a in the space between the arm 20^b and the bed plate 23. The frame or bracket 25 carries a swinging elbow lever 26 movable in a vertical plane and provided at its lower part with an arm or extension 27 on which the body or casing of the motor member 24 is detachably mounted. The 100

105

105

motor member has a shaft 28 carrying a drive pulley 29 adapted to engage the machine wheel 21 frictionally for driving the same. The motor member can be swung upwardly to engage its drive pulley 29 with the machine wheel with the proper amount of friction and can be held in that position by means of a set screw 30 on the frame or bracket 25, pressing against a portion of the lever 26, as hereinafter described. The motor member 24 is preferably located at the rear of the machine head, as shown, that is, at the side away from the operator and substantially behind the upper portion 15 of the pedestal 20^a, the drive pulley 29 being engaged with the hand wheel at the lower rear portion thereof, as shown in Fig. 3. This particular location is not, however, essential in all cases.

Referring now to the detail structure, it will be observed that the frame or bracket 25 is in the form of a plate, which may be conveniently cast with a curved laterally extending upper end 31 forming a sort of saddle abutting against the under portion 25 of the arm 20^b adjacent its junction with the pedestal. The bracket or frame 25 is detachably clamped in place between the arm and the bed plate 23, and for this purpose the upper end or saddle portion of the plate is provided with hardened metal prongs 32, which are adapted to be forced against the under portion of the arm by means of a clamping screw 33 at the lower part of the plate cooperating with the bed 23. The screw 33 has a threaded shank engaging a threaded socket in a laterally extending flange 34 cast integral with the bracket plate at its lower end, and said screw at its lower extremity is provided with a hardened point 35 adapted to bite into the upper surface of the bed 23. In order to attach the bracket or frame to the machine head in the manner shown, it is fitted 40 into the space between the arm 20^b and the bed in the relation indicated in Fig. 4, and the screw 33 is then screwed down as far as possible in its socket so as to wedge the bracket tightly in place. The hardened prongs 32 on the bracket, in connection with the hardened pointed end of the screw 33, effectively prevent the dislocation 50 of the bracket member when it has been positioned on the machine head in the simple manner explained.

At the rear edge of the bracket member, the same has an integral laterally extending tubular socket portion 36, which forms a part of the pivotal mounting for the motor supporting lever 26. This lever, at its elbow portion, is provided with a sleeve 37 having an opening registering with a threaded socket 38, in the end of the socket portion or extension 36, and a screw 39 60 passes through the sleeve and is screwed

into the socket 38 for the purpose of holding the lever 26 on the bracket member in such a manner that said lever is free to swing in a vertical plane. The screw 39 has a suitable manipulating head, and 70 between said head and the sleeve 37, a helical spring 40 is interposed, the function of which is to hold the sleeve 37 yieldingly against the socketed extension 36.

The lower arm of the elbow lever 26 is 75 provided with a lateral extension 41 directed rearwardly and horizontally, and on the arm 41 the motor supporting extension or arm 27, previously mentioned, is adjustably mounted. By referring to Fig. 1, it 80 will be seen that one end of the arm 27 is provided with a fork 42, which straddles the arm 41 from above, and a clamping screw 43 having a threaded shank engaging a threaded socket in one of the arms 85 of the fork enables the extension arm 27 to be clamped tightly to the arm 41 in the desired location. In this manner, provision is made for adjusting the motor member 24 in a forward and rearward direction, that is, toward and away from the rear face of the machine head. This adjustment is desirable in order that the drive pulley of the motor member can be engaged with machine wheels of different 90 diameters within certain limits. In Fig. 3, one of the adjustments of the arm 27, with its attached motor member, is shown in full lines, and another adjustment suitable for a machine wheel of larger diameter is 95 indicated in dotted lines.

In order to permit the drive pulley to be brought into transverse alignment with the machine wheel, regardless of the distance of the wheel from the pedestal, within certain limits, the motor member 24 is adjustable longitudinally of the arm 27. One longitudinal adjustment of the motor member 100 relatively to said arm is shown in full lines in Fig. 1 and another adjustment is shown 105 by the dotted lines. The motor member is secured on the arm 27 by means of parallel lugs 44 cast integral with the motor casing and extending downwardly therefrom at the lower portion thereof on opposite sides of 110 the arm 27. The motor member, in effect, straddles the arm 27 from above. A clamping bolt 45 extending between the two lugs 44 beneath the arm 27 and provided with a wing nut 46 enables the motor member to be 115 tightly clamped on the arm 27 in the desired longitudinal adjustment, as will be obvious.

The adjustment controlling screw 30, previously mentioned, is screwed upwardly into a sleeve-like socket 47 projecting rearwardly 120 from an arm or extension 48 on bracket 25 somewhat below the socketed extension 36. The rear end of the arm or extension 48 is 125 enlarged to form the sleeve 47 which has a vertically directed threaded socket 49 for the 130

screw 30, and the socket 47 is preferably split transversely by a kerf 50, which tends to prevent displacement of the screw 30, except when the latter is manipulated for adjusting purposes. The upper end of the screw 30 bears against the upper arm of the motor-carrying elbow lever 26. This upper arm is designated 51, and at its extremity, the lower portion thereof is abutted by the upper end of the clamping screw 30, which controls and limits the swinging movement of the motor-carrying arm 27. The screw 30 can be used for holding the motor-carrying arm in the desired position, and it can be used for giving said arm a positive upward adjusting movement. When the screw 30 is screwed upwardly in its socket, its upper end engages the arm 51 and swings the elbow lever 26 about the axis of the screw 39, so as to swing the left hand end (Fig. 1) of the arm 27 in an upward direction to a corresponding extent and thereby carry the drive pulley into engagement with the rim of the machine wheel. When the screw 30 is turned in the opposite direction, the arm 27 will move downwardly by gravity, as will be obvious, so as to disengage the machine wheel or so as to decrease the friction between the pulley and said wheel.

The operation of my device will be obvious for the most part from the foregoing description. The screw 30 supports the motor carrying arm in approximately horizontal position and prevents the motor member from swinging downwardly away from the machine wheel to any considerable extent. The provisions permitting adjustment of the motor member laterally and longitudinally relatively to the machine wheel axis have already been described. It will be obvious that the attachment can be quickly applied to machines of different makes and quickly adjusted, so that the motor member will drive the machine wheel by friction in an efficient manner, the degree of friction being controlled by the screw 30. The driving mechanism can also be detached quickly and readily, as will be obvious. The attachment, as herein described, is applicable to sewing machines having different dimensions and it can be applied to existing machines by unskilled persons without the necessity of altering the construction of such machines in any way. In other words, it is not necessary to drill holes or the like in the machine head for the application of my attachment.

In case the driving mechanism is used on a drop-head machine, it is not necessary to remove such mechanism when the head is to be dropped. At such time, the motor member is moved to the right (Fig. 1) so as to draw the drive-pulley clear of the machine wheel, and thereupon the motor member can be swung in a clockwise direction into the position shown by dotted lines in Fig. 1, in which position it is stored away substantially within the lines of the machine head. When the motor member is in this position, there is nothing to interfere with the dropping of the head into the space provided for the same in the machine table, as customary in drop-head machines. It will be understood, of course, that while the screw 30 limits the downward swinging movement of the motor member it does not interfere with the swinging movement which is required to shift the motor member to the stored away position just indicated. In moving said member to the position shown in dotted lines at the right of Fig. 1, the supporting arm structure carrying the motor and mounted on the bracket member 25 is swung upwardly and then downwardly until the drive pulley engages the bed plate 23 of the machine. In the particular example shown, the motor member in being shifted to the stored away position can be swung in a continuous motion through an arc of more than 180° , the center of which coincides with the axis of the pivoted screw 39.

Various changes can be made in the details of the construction without departure from the scope of the invention, as set forth in the claims. For example, in some aspects of the invention it is not important that the driving mechanism be detachably applied to the machine head, and in other phases of the invention it is not essential that the arms 27 and 41 exist as separate arms capable of relative adjustment. Various changes in these and other respects may be made without departing from the broad principles involved.

What I claim is:

1. The combination with a sewing machine head having a wheel at one end, of a motor member having a shaft with a friction drive pulley thereon, and means mounting said motor member so that it is movable in an approximately vertical plane upwardly into engagement with the lower portion of the machine wheel, and non-yielding means for varying the friction between the drive pulley and the machine wheel.
2. The combination with a sewing machine head having a wheel at one end, of a motor member having a drive pulley for engaging said wheel frictionally, a mounting for said motor member supporting the same for swinging movement about a horizontal axis without the motor casing so that said drive wheel engages the lower portion of the rim of the machine wheel, and means for detachably securing said mounting to the machine head.
3. The combination with a sewing machine head having a wheel, of a motor member having a drive pulley for engaging the rim of said wheel frictionally, an arm applied to the head and mounted to swing

in an approximately vertical plane, and means for securing said motor member on said arm so that the drive pulley engages the lower portion of the rim of said wheel 5 below the horizontal plane of the center of the latter, said motor member being movable to the engaged position in a substantially upward direction.

4. The combination with a sewing machine head having a wheel, of a motor member having a drive pulley for driving said wheel, an arm carrying said motor member, means mounting said arm pivotally on the machine head at a point substantially below 10 the horizontal plane of the wheel center so that the motor member is movable in a substantially upward direction into driving position, and means for holding the motor member in the driving position.

15 5. The combination with a sewing machine head having a wheel, of a motor member having a drive pulley for driving said wheel, an arm carrying said motor member, means mounting said arm pivotally on the machine head at a point substantially below 20 the horizontal plane of the wheel center so that the motor member is movable in a substantially upward direction into driving position, and means for holding the motor member in the driving position, said last 25 named means being adjustable to vary the driving action.

6. The combination with a sewing machine head having a wheel, of a motor member for driving said wheel frictionally, and means for mounting said motor member in a plane below said wheel axis including a supporting arm for said motor member secured thereto and directed lengthwise of 30 the head at the rear of the latter, and means for securing said arm on the head so that it is movable in an approximately vertical plane to carry the motor member into and 35 out of the operative position, the motor member being movably mounted on said arm.

7. The combination with a sewing machine having a wheel, of a motor member having a pulley for engaging said wheel frictionally to drive the same, and means 40 for mounting said motor member in a plane below said wheel axis including a supporting arm for said motor member directed substantially longitudinally of the head at 45 the rear thereof and having a pivotal mounting whereby said arm is movable in an approximately vertical plane, and means for securing said pivotal mounting detachably to the sewing machine head, the motor member being movably mounted on said arm.

8. The combination with a sewing machine head having a wheel, of a motor member having a drive pulley for engaging said wheel frictionally, means upon said 50 head mounting said motor member below

said wheel axis so that it is movable to carry said drive pulley upwardly into engagement with said wheel, and means for giving the motor member a positive upward adjusting movement.

9. The combination with a sewing machine head having a wheel, of a motor member, mounted on said head, having a drive pulley for engaging the lower part of said wheel frictionally, and positively 70 acting means for moving the motor member toward the wheel so that the drive pulley will engage the latter with the desired amount of friction.

10. The combination with a sewing machine head having a wheel, of a motor member having a drive pulley for engaging the lower part of said wheel frictionally, means upon said head for mounting said motor member swingingly relatively to said wheel, and positively acting means for holding the drive pulley against the wheel.

11. The combination with a sewing machine head having a wheel, of a motor member having a drive pulley for engaging said wheel frictionally, means upon said head for mounting said motor member swingingly relatively to said wheel, and positively and upwardly acting means for holding the drive pulley against the wheel, 85 said last named means being adjustable to vary the degree of frictional contact.

12. The combination with a sewing machine head having a wheel, of a motor member having a drive pulley for engaging said wheel frictionally, means mounting said motor member for swinging movement relatively to said wheel, and means comprising a vertical adjusting screw for holding the drive pulley in engagement with said wheel in a positive manner and preventing it from moving away from said wheel.

13. The combination with a machine having a head and wheel, of a motor member having a drive pulley for frictionally engaging said machine wheel to drive the same, means comprising a vertical adjusting screw for forcing said drive pulley into engagement with the machine wheel and controlling the frictional engagement between said parts.

14. The combination with a machine having a head and wheel, of a motor member having a drive pulley for frictionally engaging said machine wheel to drive the same, and means comprising a vertical adjusting screw for forcing said drive pulley into engagement with the machine wheel and controlling the frictional engagement between said parts, said motor member being movable substantially upwardly into the engaged position.

15. A sewing machine driving attachment, comprising a motor member, a supporting frame therefor, and means for se- 130

- curing the supporting frame to the machine head between the sewing machine arm and the bed plate.
16. A sewing machine driving attachment, comprising a motor member, a supporting frame for the same, and means for detachably securing the supporting frame in the space between the sewing machine arm and bed plate.
- 10 17. A sewing machine driving attachment, comprising a motor member, a supporting frame therefor, and means for securing the supporting frame along side the pedestal of the sewing machine head and beneath the sewing machine arm.
- 15 18. A sewing machine driving attachment, comprising a motor member, a supporting frame therefor, and means for detachably securing said supporting frame to the machine head along side the machine pedestal and in the space between the sewing machine arm and the bed plate of the machine.
- 20 19. A sewing machine driving attachment, comprising a motor supporting frame, and wedging means for securing said frame in the space between the sewing machine arm and the bed plate.
- 25 20. A sewing machine driving attachment, comprising a motor supporting frame, and adjustable wedging means for wedging said frame within the outlines of the sewing machine head.
- 30 21. A sewing machine driving attachment, comprising a motor supporting frame, and means for securing said frame tightly in place between the laterally extending sewing machine arm and the bed plate.
- 35 22. A sewing machine driving attachment, comprising a supporting frame, and means comprising an adjustable screw, for wedging the same in place between the sewing machine arm and the bed plate of the machine.
- 40 23. In combination with a sewing machine head having a bed plate, and a lateral arm above the bed plate, a frame detachably interposed between said arm and bed plate.
- 45 24. In combination with a sewing machine head having a bed plate, and a lateral arm above the bed plate, a member detachably interposed between said arm and bed plate, and a motor for driving the machine mounted on said member.
- 50 25. In combination with a sewing machine head having a bed plate, and a lateral arm above said bed plate, said head also having a wheel, a frame wedged in place between the arm and bed plate, and a motor member supported on said frame for driving the machine wheel.
- 55 26. In combination with a sewing machine head having a pedestal and a lateral arm, said head also having a wheel, a motor member for driving the wheel, and a sup-
- porting member for said motor member located at the inner side of the pedestal beneath the arm.
27. In combination with a sewing machine head having a wheel, a pedestal on which the wheel is mounted, and a laterally extending arm at the top of the pedestal, a motor member having a drive pulley for engaging the machine wheel frictionally, a supporting member for said motor member, and means for detachably securing said supporting member in engagement with the pedestal and arm.
- 70 28. The combination with a sewing machine having a wheel, of a motor member having a pulley for driving said wheel frictionally, and means for mounting said motor member for longitudinal movement in an approximately vertical plane, said motor member also being swingable away from the machine wheel into a stored position substantially within the lines of the sewing machine head.
- 75 29. The combination with a sewing machine having a wheel, of an arm on the head directed substantially lengthwise thereof and adapted to swing in an approximately vertical plane, and a motor member for driving the wheel adjustably mounted upon said arm and movable with the latter in a downward direction to a stored away position.
- 80 30. The combination with a sewing machine having a wheel, of a motor member having a pulley for driving said wheel frictionally, a swinging arm on the head adapted to swing in an approximately vertical plane and carrying said motor member, said motor member being adjustably mounted on said arm and movable upwardly to engage said drive pulley with the lower portion of the machine wheel, and said motor member being swingable upwardly and downwardly when the drive pulley is withdrawn from the machine wheel, for the purpose of moving said motor member downwardly to a stored away position adjacent the bed plate of the sewing machine.
- 85 31. A sewing machine driving attachment, comprising a swinging supporting arm, a mounting therefor, and a motor member on said arm adjustable longitudinally thereof.
- 90 32. A sewing machine driving attachment, comprising a swinging supporting arm, a mounting therefor, a motor member slideable lengthwise along said arm, and means for securing said motor member in the desired longitudinal adjustment.
- 95 33. A sewing machine driving attachment, comprising a swinging supporting arm, a motor member slideable lengthwise on said arm, means for securing the motor member in the desired longitudinal adjustment, a frame on which said arm is mount-
- 100 110 115 120 125 130

ed, and an adjusting screw on the frame cooperating with the arm.

34. A sewing machine driving attachment, comprising a swinging supporting arm, a motor member slidably lengthwise on said arm, means for securing the motor member in the desired longitudinal adjustment, a frame on which said arm is mounted, and an adjusting screw on the frame 5 cooperating with the arm, said swinging arm being limited in its movement in one direction by said screw, but being movable

freely away from the screw in the other direction to carry the motor member to a stored away position.

35. In a motor attachment for sewing, and like machines having a drive wheel, a motor supporting member pivotally mounted adjacent the drive wheel and a motor member slidably mounted on said support. 15 20

In witness whereof, I have hereunto set my hand on this 7th day of June, 1919.

EDWARD N. ANKETELL.
